Des. 236,059
Patented July 29, 1975

236,059

RECORD HOLDING DEVICE

Julian Gutierrez, 6233 Brookview Ave.,
Minneapolis, Minn. 55424

Term of patent 14 years

Int. Cl. D6—04

U.S. Cl. D6—185

FIG. 1

FIG. 2

FIG. 3

FIG. 4

FIG. 5

FIG. 1 is a top plan view of a record holding device showing my new design;

FIG. 2 is a view thereof in side elevation;

FIG. 3 is a bottom plan view thereof;

FIG. 4 is a view in elevation in one end thereof; and FIG. 5 is a view in elevation of the other end thereof. I claim:

The ornamental design for a record holding device, as shown and described.
